UNITED STATES PATENT OFFICE.

JOHN F. O'CONNOR, OF CHICAGO, ILLINOIS, ASSIGNOR TO W. H. MINER COMPANY, OF CHICAGO,
ILLINOIS, A CORPORATION OF ILLINOIS.

FRICITION DRAFT-RIGGING FOR RAILWAY-CARS.

No. 922,617.

Specification of Letters Patent.

Patented May 25, 1909.

Application filed November 20, 1908. Serial No. 463,555.

To all whom it may concern:

Be it known that I, JOHN F. O'CONNOR, a citizen of the United States, residing in Chicago, in the county of Cook and State of Illinois, have invented a new and useful Improvement in Friction Draft-Rigging for Railway-Cars, of which the following is a specification.

My invention relates to improvements in friction draft rigging for railway cars.

Many cars now in use are equipped with the well known tandem spring draft rigging having two springs arranged tandem, four followers, one on each end of each spring, and 15 side plates or stop castings having front, rear middle and intermediate stops or shoulders for the followers to abut against; and it is sometimes desired to apply a friction cushioning mechanism to such cars without re- 20 moving therefrom the tandem draft rigging side plates or stop castings. And the object of my invention is to provide a friction cushioning mechanism of a simple, efficient and durable construction which will be adapted 25 for use in and to coöperate with the side plates or stop castings of an ordinary tandem spring draft rigging, and with the draw bar and draft yoke thereof without further change.

30 My invention consists, in connection with the draw bar, draft yoke and side plates or stop castings of an ordinary tandem spring draft rigging and its front and rear followers, of a spring abutting at one end against one of the followers, a friction mechanism, comprising a longitudinally movable friction shell, a pair of friction shoes and a wedge with anti-friction rollers interposed between the wedge and shoes, the wedge bearing against the 35 other follower, and an intermediate follower bearing against the inner end of the spring and adapted to abut against one of the middle stops, and having an extension or member projecting between the middle stops of 40 the side plates and bearing against the rear end of the friction shoes, and a coupling member secured to the rear follower and extending through the spring and adapted at its front end to engage the friction shell and 45 having coupling lugs adapted to interengage with coupling lugs on the shell member of the friction mechanism.

50 My invention also consists in the novel construction of parts and devices and in the novel combinations of parts and devices

herein shown and described and specified in the claims.

In the accompanying drawing forming a part of this specification, Figure 1 is an elevation, partly in central vertical longitudinal section, of a friction draft rigging embodying my invention; Fig. 2 is a longitudinal section on line 2—2 of Fig. 1; Figs. 3, 4 and 5 are cross sections on lines 3—3, 4—4 and 5—5, respectively, of Fig. 1; Fig. 6 is a detail plan 65 view of the wedge of the friction mechanism; Fig. 7 is a detail plan view of one of the friction shoes; Fig. 8 is an elevation of the same; Fig. 9 is a detail view of the intermediate follower; Fig. 10 is a detail rear end elevation of 70 the friction shell, and Fig. 11 is a detail elevation of the friction shell.

In the drawing A represents the center sills or other draft members of the car frame to which the side plates or stop castings are 75 secured, A¹ the front or end sill, B the draw bar, B¹ the draft yoke, C C¹ the front and rear followers, and D D the side plates or stop castings having front, rear middle and intermediate stops d¹ d² d³ d⁴ d⁵ d⁶ d⁷ for the fol- 80 lowers to abut against, the side plates D being of the ordinary construction commonly employed in a tandem spring draft rigging.

E E¹ are the springs abutting at their rear ends against the rear follower C¹.

85 F is a longitudinally movable friction shell, G friction shoes within the shell, G¹ a wedge between the friction shoes, G² anti-friction rollers interposed between the wedge and the inclined or wedging faces g of the friction shoes.

H is an intermediate follower bearing at its rear end against the front end of the spring and at its front end against the rear end of the friction shoes, and M is a coupling member bearing at its rear end against the rear follower and adapted to bear at its front end against the rear end of the friction shell.

95 The longitudinally movable friction shell F is adapted to abut at its rear end shoulders f against the front middle stop d² and also against the intermediate stop d⁵; and it is provided with an internal transverse web f¹ and with extensions f² having coupling lugs f³. The rear ends of said extensions f² are 100 adapted to abut against shoulders m of the coupling member M. The coupling member M is preferably of tubular form and secured at its rear end by a screw m¹ to the rear follower C¹, and it is provided at its front end 105

110

with a coupling head m^2 having coupling lugs m^3 adapted to interengage with the coupling lugs f^3 of the friction shell F. The coupling member M is adapted to abut at its front end 5 m^4 against the inwardly projecting shoulder f^4 on the friction shell F. The coupling head m^2 of the coupling member M is adapted to enter the friction shell F through an elongated opening or slot f^5 therein, so that after 10 the coupling member is so entered within the friction shell the coupling lugs of the friction shell and coupling member will interengage by turning one part in respect to the other.

The intermediate longitudinally movable 15 follower H has an extension or member h preferably integral therewith, which projects between the middle stops d^2 d^2 d^3 d^3 of the side plates D, and abuts at the front end h^1 thereof against the friction shoes G, so that the 20 spring will act against the friction shoes in both pulling and buffing. The intermediate follower H is preferably in two separate pieces or halves having a central space or opening h^2 between them to receive the coupling member M, and to accommodate the 25 coupling head m^2 thereof.

The friction shell F and the coupling member M have a limited sliding movement, one in respect to the other, and the intermediate 30 follower H has a similar limited movement in the opposite direction before engaging the middle stop d^3 , as will be readily understood from Fig. 2 of the drawing; this provides for a limited preliminary compression of the 35 spring in both pulling and buffing before the cushioning mechanism comes into operation, and enables the draft rigging to more efficiently cushion light shocks or blows while not interfering with its efficient cushioning of 40 heavy ones. The springs E E^1 are or may be one of the two sets of springs previously used in the old tandem spring gear which is replaced in the car by my new improved friction and spring cushioning mechanism.

45 The side plates or stop castings have in addition to the front, rear and middle stops d d^2 d^3 also the customary intermediate stops d^4 d^5 d^6 d^7 and the frontmost intermediate stop d^4 coöperates with the front follower to 50 limit the compression of the cushioning devices in buffing and the rearmost intermediate stop d^8 coöperates with the rear follower to so limit the compression in pulling, and the other two intermediate stops similarly 55 coöperate with the intermediate follower H and the shoulder f of the friction shell F.

I claim:

1. In a friction draft rigging, the combination of the draw bar, draft yoke, front and 60 rear followers and side plates having the front, rear, and middle stops of an ordinary tandem spring draft rigging, of a combined spring and friction cushioning mechanism coöperating therewith, said spring and cushioning mechanism being adapted to be sub-

stituted for the tandem springs and two intermediate followers of the ordinary tandem spring gear, said combined spring and friction cushioning mechanism comprising a longitudinally movable friction shell having 70 shoulders adapted to abut against the forward middle stops, and friction shoes within said shell, and an intermediate follower adapted to abut against the rearmost middle stop and having an extension projecting longitudinally between the middle stops and bearing against the friction shoes, substantially as specified.

2. In a friction draft rigging, the combination of the draw bar, draft yoke, front and 80 rear followers and side plates having the front, rear, and middle stops of an ordinary tandem spring draft rigging, of a combined spring and friction cushioning mechanism being adapted to be substituted for the tandem springs and two intermediate followers of the ordinary tandem spring gear, said combined spring and friction cushioning mechanism comprising a longitudinally movable friction shell having shoulders adapted to abut 85 against the foremost middle and an intermediate follower having an extension projecting longitudinally between the middle stops and bearing against the friction shoes, a coupling member bearing at its rear end against the 90 rear follower and adapted to abut at its front end against said friction shell, and said friction shell and coupling member having interengaging coupling lugs, substantially as specified.

3. In a friction draft rigging, the combination with side plates having front, rear and middle stops, of a draw bar, draft yoke, front and rear followers, a spring, a friction shell, friction shoes within the shell, a 105 wedge, antifriction rollers between the wedge and friction shoes, an intermediate follower extending between said intermediate stops of the side plates and bearing at one end against the friction shoes and at the other end against the spring, and a coupling member bearing at one end against one of the followers and at the other end against the friction shell, said friction shell being adapted to engage one of said middle stops and the intermediate follower the other thereof, substantially as specified.

4. In a friction draft rigging, the combination with side plates having front, rear and middle stops, of a draw bar, draft yoke, front 120 and rear followers, a spring, a friction shell, friction shoes within the shell, a wedge, antifriction rollers between the wedge and friction shoes, an intermediate follower extending between said middle stops of the side 125 plates and bearing at one end against the friction shoes and at the other end against the spring, said friction shell being adapted to engage one of said middle stops and the intermediate follower the other thereof, said 130

friction shell and coupling member having coupling lugs adapted to interengage by turning the one in respect to the other, substantially as specified.

5. In a friction draft rigging, the combination with side plates having front, rear and middle stops, of a draw bar, draft yoke, front and rear followers, a spring, a friction shell, friction shoes within the shell, a wedge, anti-friction rollers between the wedge and friction shoes, an intermediate follower extending between said middle stops of the side plates and bearing at one end against the friction shoes and at the other end against the spring, and a coupling member bearing at one end against one of the followers and at the other end against the friction shell, said friction shell being adapted to engage one of said middle stops and the intermediate follower the other thereof, and a connecting link between the friction shell and wedge, substantially as specified.
10. In a friction draft rigging, the combination with side plates having front, rear and
15. lower the other thereof, and a connecting link between the friction shell and wedge, substantially as specified.
20. 6. In a friction draft rigging, the combination with side plates having front, rear and

middle stops, of a draw bar, draft yoke, front and rear followers, a spring, a friction shell, friction shoes within the shell, a wedge, anti-friction rollers between the wedge and friction shoes, an intermediate follower extending between said middle stops of the side plates and bearing at one end against the friction shoes and at the other end against the spring, said friction shell being adapted to engage one of said middle stops and the intermediate follower the other thereof, said friction shell and coupling member having coupling lugs adapted to interengage by turning the one in respect to the other, and said friction shell and coupling member having a limited sliding movement one on the other to provide for a preliminary spring cushioning action before the friction cushioning devices come into action, substantially as specified.
